MEANS FOR HANDLING A SHIP'S
LIFEBOAT

Ane Pieter Schat, Utrecht, Netherlands

Application October 25, 1933, Serial No. 695,191

2 Claims. (Cl. 9—22)

This invention relates to means for handling a ship's lifeboat.

The main object of the invention is to provide for a manually operable davit installation, which enables the boat to be launched also on the high side of a vessel having a considerable list, requires relatively very little power for its operation, permits of deck space being gained for passengers and increases the access of light to deck cabins, if any.

With these and other objects in view, I suggest to suspend the lifeboat from a luffing davit, or a pair of such davits adapted to travel along a trackway disposed athwart-ships and to associate said davit, or davits, with rigid means, such as an expansible and contractible member for positively forcing the davit, or the davits, along said trackway towards or away from the water, and for luffing the same, if so desired.

The invention is illustrated in the accompanying drawing, in which

Fig. 1 is a general view of an installation embodying the invention,

Fig. 2 is a side view of the davit and of its trackway, looking from the left hand side in Fig. 1, and

Fig. 3 shows the expansible and contractible member, drawn to an enlarged scale, partly in elevation and partly in longitudinal section.

As shown, the lifeboat 4 is suspended from a pair of luffing davits, of which only one has been illustrated and designated by the numeral 5.

Said davit has an enlarged base or foot portion forming a slide fitted with two pairs of rollers 6, 6' and 7, 7', by means of which the davit is adapted to travel on the steel deck 8 towards and away from the water. Said rollers are rotatable about trunnions 9, 9' and 10, 10', which laterally project therefrom and are guided by the lower faces of the inturned horizontal top flanges of two Z-irons 11, 12, the bottom flanges of which are fastened to the steel deck 8, it being understood that the said top flanges are flush with the wooden deck 13.

A certain distance above the trackway 11, 12, the davit 5 is provided, on its outboard side, with laterally extending trunnions 14, 15 adapted, at the end of the outward movement of the davit along its track, to enter into notches 16 of a bracket 17 bolted or otherwise secured to the steel deck near the edge thereof. Said bracket is provided with some conventional means whereby the trunnions 14, 15, after entering the said notches 16, may be locked so as to be prevented from inboard movement but to have freedom of

rotary movement within the notches of the brackets which, therefore, act both as bearing blocks and as stoppers.

As clearly seen from Fig. 1, the Z-irons 11, 12 end a certain distance from the stoppers 17, whereby gaps 18 are formed allowing the trunnions 9, 9' to pass. The Z-irons 11, 12 are each provided with a recess 19 spaced from gap 18 through a distance equal to that between the pairs of rollers 6, 6' and 7, 7'.

Intermediate the gaps 18 and the recesses 19, the runners 11, 12 have additional recesses 20, and intermediate the pairs of rollers 9, 9' and 10, 10' the davit foot is provided with laterally projecting pins 21 which, during the travelling movement of the davit along its trackway, also engage the lower faces of the top flanges of the runners 11, 12.

Between its top and its foot, the davit 5 is hinged to a substantially horizontal, expansible and contractible member 22 shown in further detail in Fig. 3, and whose inner end is pivoted as at 23 to a deckhouse or other fixed structure of the vessel at a height of say 6' 10" above the deck. Said member is composed of a tube 24 provided with a lug 25 for receiving the horizontal pivot 23, and with a nut member 26 at its outboard end operatively engaged by a hollow screw spindle 27. The latter, the inward end of which is provided with a collar 27a, also has a nut member 28 at its outboard end in engagement with a solid screw spindle 29, the inner end of which is provided with a collar 29a and the outer end of which carries a mitre wheel 30 (Fig. 2) meshing with a second mitre wheel 31 on a horizontal shaft 32. Said shaft runs in the longitudinal direction of the vessel and is supported in bearings of the davit 5. Its free end carries a cast wheel 33 having a circumferential groove 34 of V-shaped cross section, it being understood that the side walls of said groove are not machined, but rough. Passed around wheel 33 is an endless operating rope 35.

It may be stated here that the pitch of the screw thread on spindles 27 and 29 is so small that both spindles are self-braking, so that there is no danger for the davit on the low side of a vessel having a considerable list to move downhill towards the water under the influence of gravity only.

Near its foot, the davit 5 is provided with a small bollard 36, and coaxially with shaft 32 it has a fixed guide roller or sheave 37 serving as a fairlead for the boat's fall 38.

The lower end of the davit is further provided

with a rest 39 for supporting the keel 40 of the stowed boat. Said rest is engaged by one end of the boat lash 41, the other end of which is adapted to be secured to the davit by means of 5 a slipguard link not shown on the drawing.

The boat 4 is suspended from the davit 5 in the ordinary manner by means of manila falls 38, each of which is passed over sheaves 42 rotatably mounted in the head of the corresponding davit 10 5 and sheaves 43 rotatably mounted in the steel house 44 of the lower block. Said house is fitted with an eye 45 which through a slipguard link 46 and a chain 47 is suspended from the davit head.

15 The modus operandi of the described installation is as follows.

If the davit 5 and the boat 4 assume the position shown in full lines, the multiple telescopic screw spindle gear is collapsed and has its minimum length. If, then, wheel 33 is turned by 20 means of rope 35, the solid screw spindle 29 will be rotated through the medium of the mitre wheels 31 and 30, whereby, owing to the co-operation of said screw spindle with its nut 28, the member 22 is expanded. It is to be remarked 25 that, since the V-groove in the wheel 33 is not machined, so that its walls have a rough surface, the rope 35 cannot slip under any pull that is likely to be exerted on the hauling part thereof.

30 If screw spindle 29 is rotated, its nut 28 will remain stationary, abstracting from its axial movement, until it is engaged by collar 29a. Thereupon, further rotation of screw spindle 29 will cause rotation of the hollow screw spindle 35 27 relative to its nut 26, whereby said last spindle is screwed out of its tube 24 and the member 22 is still further expanded, until collar 27a abuts against nut 26, when member 22 has reached its maximum length.

40 During the first part of the expansion of member 22, the davit 5 is moved in outward direction along its trackway 11, 12, until its trunnions 14, 15 abut against the bottom walls of the notches 16 of the stopper 17, in which notches said trunnions are locked against inboard movement, either manually or automatically. The position 45 then assumed by the davit is shown by dotted lines. As will be seen, the boat 4 is then half-way outboard with its keel 40 vertically above the side of the vessel, and may be left there as long 50 as the vessel is at sea. With the boat in this position, the light has better access to deck cabins, if any, and a considerable amount of deck space is gained for the passengers. Preferably, 55 the inboard parts of the tracks for the davit are then covered with wooden grates so as to provide for a flush walking space.

When it is desired to launch the boat, the lashings 41 are released. This can be done in the 60 usual manner by means of slip-guard links (not shown) on the inboard side. Thereupon, the member 22 is further expanded by again pulling on the rope 35, whereby the davit 5 is swung in 65 anticlockwise direction about its trunnions 14, 15, until the boat has reached its extreme outboard position and can be lowered.

It will be seen from the drawing that in the outboard position of the davit 5 the trunnions 9, 9' and 10, 10' of the rollers 6, 6' and 7, 7' 70 register with the gaps 18 and 19, respectively, and that the laterally projecting pins 21 then register with the gap 20, so that the davit has freedom of swinging motion about its trunnions 14, 15.

If the vessel has a considerable list, the davits 75 on the low side need not be swung out, as the

boats on that side already assume a position vertically above the water, after their lashings 41 have been released. Since the screw spindles 27 and 29 are self-braking, the davit in its dotted line position cannot swing out unless wheel 33 is 5 positively turned by means of the rope 35.

It will further be understood that, when the boat is provided with so-called "skates", as described, for instance in my prior British Patents 252,014, January 6, 1927; 255,727, July 26, 1926; 10 257,300, August 26, 1926; and 259,148, October 7, 1926, the boat can be launched without the davit in its dotted line position being swung out (provided the davit is not on the high side of a heavily listed vessel) and the skates will then guide 15 the boat down the ship's hull. When the boat is so lowered, it will be pressed against the ship's side owing to the top blocks of its tackles being inboard, whereby the embarkation of passengers and crew is facilitated. 20

In order that the boat can be lowered, it is necessary first to release the slipguard link 46, and thereupon to pay out the fall 38. In this connection it is remarked that the provision of the chain 47 with its slipguard link 46 provide a ready 25 means for relieving the fall, and thereby the sheaves and pins of the blocks, from tension when the boat assumes its stowed position. In order that the boat may thus be suspended from the chains 47, it is necessary to first hoist it by 30 its falls until the slipguard links 46 can be closed and locked.

The fall 38, which is passed over the sheaves of the lower block and of the top block, is first led 35 over pulley 37, which is secured to the davit arm and locked against rotation, and thereupon belayed on bollard 36 secured to the davit arm on the inboard side thereof. This construction has the advantage that no holes are to be drilled in the steel deck 8 for fastening said bollard and 40 also, that the bollard follows the lateral and swinging movements of the davit, so that the men who pay out the fall can always keep their eyes upon the boat, even when the latter is near 45 the surface of the water. Owing to the presence of the fair lead 37, which, during the lowering of the boat, by its friction takes up a considerable part of the tension in the fall, the bollard 36 may be relatively small. When the boat is to be hoisted, however, the fall is taken 50 off said fixed fairlead and its hauling part then runs from the top block directly to a removable footblock on deck and thence to a winch, both not shown.

Obviously, the unique arrangement wherein 55 the luffing davit, in addition to its swinging movement, must also be adapted to travel through a considerable distance over the deck, requires an expandible member 22 of considerable maximum length. Up till now, members of this 60 type always consist of a tube provided with a nut, and one single screw spindle engaging said nut, so that their maximum length is at most equal to twice its minimum length. With a construction as shown in Fig. 3, however, wherein 65 the screw spindle 27 is hollow and is itself provided with a nut 28 coaxing with a second screw 29, the length of member 22 in fully expanded condition is about thrice that in collapsed condition, so that said construction is especially 70 adapted for use with davits of my novel type.

It will be remarked that member 22, which is substantially horizontal when the davit assumes its inboard position shown in full lines, remain substantially horizontal until the davit has 75

reached its outboard position illustrated in dotted lines. Only thereafter, further rotation of wheel 33 will cause the davit to swing about its trunnions 14, 15, during which movement the point in which member 22 engages the davit first rises and thereafter descends. However, since during this swinging movement member 22 has already a considerable length, its deviation from the horizontal will not become very appreciable, so that said member always engages the davit under a favorable angle.

With a view to the fact that the lateral outboard movement of the davit will, as a rule, require less power than the first part of the swinging movement, the pitch of the screw spindle 29 preferably exceeds that of screw spindle 27, although it must remain below the limit at which it would lose its self-braking action.

What I claim is:—

1. In combination, a davit adapted for luffing movement and a telescopic member for controlling said movement, said member comprising a tubular element provided with female thread, a hollow externally threaded screw spindle engaging said female thread so as to be freely rotatable and axially movable relative to said tubular element and provided with female thread, hav-

ing a pitch different from that of its external thread, a second screw spindle engaging the female thread of the hollow screw spindle so as to be freely rotatable and axially movable relative to both said hollow screw spindle and said tubular element, and means on said hollow screw spindle and on said second screw spindle for limiting said axial movements. 5

2. In an installation for launching a lifeboat on board a vessel comprising a substantially straight trackway provided athwartships on a vessel, an upright davit arm movable on said trackway and maintained in upright position during travel thereon, substantially horizontal pivot means for limiting the outboard movement of said davit arm, said pivot means including a pivot element on the davit arm and a pivot element fixed on the ship above the trackway and engageable by the first mentioned pivot element when the davit arm is in outboard position, 20 whereby said davit arm may perform a luffing motion about the horizontal axis of said pivot means, and means for moving the davit arm along said trackway and for swinging it about said axis. 25

ANE PIETER SCHAT.
